C. B. CLARKSON,
COMBINED VALVE RESEATING TOOL,
APPLICATION FILED JUNE 6, 1914.

1,183,855.

Patented May 23, 1916

UNITED STATES PATENT OFFICE.

CLAUDE B. CLARKSON, OF BRIDGEPORT, CONNECTICUT.

COMBINED VALVE-RESEATING TOOL

1,183,855.

Specification of Letters Patent.

Patented May 23, 1916.

Application filed June 6, 1914. Serial No. 843,423.

To all whom it may concern:

Be it known that I, CLAUDE B. CLARKSON, citizen of the United States, and resident of Bridgeport, in the county of Fairfield and 5 State of Connecticut, have invented certain new and useful Improvements in Combined Valve-Reseating Tools, of which the following is a specification.

This invention relates to new and useful 10 improvements in a combination valve and valve stem reseating tool.

It is the object of the invention to produce a new form of tool of the above class which will be simple and compact in design and 15 which will be adapted for reseating both valve seats and valve stems, thus forming two tools in one; further to so arrange and design the parts as to adapt it to be operated as in reseating a valve with an ordinary 20 screw driver and further to adapt it to be used in connection with a special form of operating handle for reseating a valve seat, and finally to provide a series of cutting blades alike in construction and the opposite 25 ends of which form the cutting edges for the respective reseating operations; and finally to arrange these blades so that they may be readily removed and replaced if occasion requires.

30 With the above and other objects in view the invention resides and consists in the novel construction and arrangement of parts shown upon the accompanying sheet of drawings forming a part of this specification and upon which—

Figure 1 shows a side elevation of my novel form of valve and valve stem reseating tool. Fig. 2 is a central vertical longitudinal section of the said tool as shown in 40 Fig. 1 and taken on line 2—2 of Fig. 3. Fig. 3 is a top plan view of the tool as seen in Fig. 1. Fig. 4 is a bottom plan view of the same. Fig. 5 is a further central vertical longitudinal section through the said 45 tool and taken on line 5—5 of Fig. 3. Fig. 6 represents a valve such as the upper end of the tool is designed to trim up as in the reseating operation and Fig. 7 is an operating handle that is designed to be used in the 50 operation of my improved reseating tool.

As before stated the tool is what I term a combined tool and serves to form two tools in one both of which are designed for valve grinding or reseating work, one end of the tool being designed for operating upon the valve seat and the other upon the valve,

and so that when each has been operated upon they will properly fit one upon the other as is required for the successful operation of a motor of which they form a part.

My device is designed for reseating the ordinary form of gasoline motor valves including the annular beveled seat and the annular conical valve and thus one portion 65 of the tool is of a somewhat conical formation to perform the operation upon the valve seat, while the other portion or end is concaved or of a funnel shape to operate upon the valve. Therefore one end of the device 70 is in form and shape just the reverse of the other. In the reseating operation of the valve seats the tool is designed to be rotated or turned upon and within the seat by means of an attached handle, while in the operation 75 upon the valve proper the tool is held stationary while the valve and its stem are turned within the tool by the assistance of an ordinary screw driver.

Referring in detail to the characters of 80 reference marked upon the drawings 10 represents the main body of the tool and which is obviously formed of steel or other suitable metal and is of a general cylindrical shape, see Fig. 5, having a central hole 11 85 therethrough, an annular peripheral tapered edge portion 12 surrounding its lower end, and a conical recess 13 in its upper end. In addition to the several features of the body referred to I also provide a transverse slot 90 14, see Figs. 2 and 3, in its upper end which serves to be engaged by the pin 15 of the operating handle 16. I further provide in the outer face of the body a series of longitudinal arranged pockets 17 which in practice are 95 milled to a uniform width and depth to receive the cutting blades 19. In practice I have shown four of these blades and pockets, but obviously a greater or lesser number may be employed if desired.

100 The cutting blades are preferably formed slightly longer than the body and are provided with an outer beveled cutting edge 20 which in practice projects beyond the peripheral surface 12 of the body and an inner beveled cutting edge 21 upon the upper end which like that of the lower end also projects above and beyond the beveled end 13 of the body. The outer edge portions of these cutting blades are notched or recessed as at 22 110 to receive the annular band or cylinder 23 which serves to hold the blades in position.

The upper edge portion of the band seats against the annular shoulder 24 formed by the annular flange 25 of the body. A set screw 26 may be employed to hold the band and blades in position, though they may be driven or shoved on so as to form a drive fit in a way to hold them in position without the screw.

In assembling the parts the blades are first arranged inside of the band and their end portions 21 are first inserted in the slots of the body whereupon the several blades and band are all shoved in together until the band is seated against its shoulder and the ends of the blades extend into the upper pocket of the body in the manner indicated.

I have shown in Fig. 1 the handle 16 arranged in position for the operation of the tool as in the grinding of a valve seat. The reduced lower end of the handle being extended through the hole 11 of the body and the pin 15 seated in the notch 14 of the body so as to insure the turning of the body with the tool. A suitable cross finger piece 27 forms a part of the handle so as to insure the easy operation of the device.

In Fig. 5 the valve 28 shown in Fig. 6 is shown in dotted lines in position to be operated upon. The downwardly extended stem of the valve in this instance freely passes through the hole 11 of the body while the annular beveled edge portion of the valve rests upon the inclined cutting edges 21 of the blades in a way to be operated upon by them when the valve is turned by the assistance of a screw driver, not shown.

From the foregoing it will be seen that the tool is a combined tool and serves the double purpose of operating upon both the valve and valve seat, and thus includes all the necessary tools and equipment for reseating

ordinary motor valves and seats and can obviously be made at a reasonable cost so as to sell for less than what two or three separate tools would cost and as is now necessary 45 for performing these same operations.

Having thus described my invention what I claim and desire to secure by Letters Patent is:—

1. A combined reseating tool for reseating valves and valve seats, including a body portion having a hole therethrough and an external annular flange forming a shoulder, a series of cutting blades seated in the body and arranged parallel to each other, the said blades projecting beyond the end of the body to form a cutting edge and having a notch in their outer edge portion, a removable band extending around the body and through the said notches of the blades and seated against the shoulder of the body to hold the blades in position. 50

2. A combined reseating tool for reseating valves and valve seats, including a body portion having a hole therethrough and a notch adjacent to one end thereof to receive an operating handle, a series of radially and longitudinally disposed cutting blades seated therein and having a recess formed in their outer edge portion, the ends of the said blades projecting beyond the opposite end portions of the body and beveled off to form cutting edges, a removable band surrounding the body and blades to secure the latter in position. 65

Signed at Bridgeport, in the county of Fairfield and State of Connecticut, this 5th day of June, A. D. 1914.

CLAUDE B. CLARKSON.
